SYRINGE

Joseph Vondrak, New York, N. Y.

Application October 28, 1941, Serial No. 416,856

11 Claims. (Cl. 128—215)

The present invention relates to syringes and particularly to the type in which adjustment can be made to predetermine the dosage as for instance is desirable in a hypodermic syringe.

An object of this invention is to provide a simple article of novel and improved construction, which is adapted to be easily attached to a syringe having a graduated cylinder, and to serve to determine the quantity of material to be ejected, and be adjustable to change the quantity as may be required, or adaptable for identical volume delivery.

Another object hereof is to provide a novel and improved article of the character mentioned, which is easy to use, cheap to manufacture and efficient in carrying out the purposes for which it is designed, and further it shall not interfere with the operation, assembly, dismantling or cleaning of the syringe proper.

Other objects and advantages will become apparent as this disclosure proceeds.

In the accompanying drawing forming part of this application, similar characters of reference indicate corresponding parts in all the views.

Fig. 1 is a perspective view showing one embodiment of the teachings of this invention.

Fig. 2 shows the same as mounted on a syringe.

Fig. 3 is an enlarged fragmentary section of Fig. 2.

Fig. 4 shows another embodiment of this invention.

In the drawing the numeral 10 designates generally a syringe or similar device, comprised essentially of a cylinder or barrel 11, in which is an outwardly extending handled piston 12, for movement of fluid 13, through the nozzle 14. The cylinder is preferably graduated by lines which may be grooved in its exterior surface, as *a*, *b* and *c*, constituting a suitable scale indicating volumetric measure. The piston 12, may carry thereon an adjustably positioned stop element, as for instance the sleeve designated by the numeral 15.

An arm 16, has its ends 17 and 18 bent towards one side thereof. The end 17, may be bifurcated and extends straddling the piston 12 with its tines 17' close enough to each other to intercept the extending flange 15' of the element 15, when the piston 12 is slid into the barrel 11. The arm 16, in the region of its end 18, has pivotally secured thereto a spring clamp 19, the body of which extends from said pivotal connection 20, towards the aforesaid tines 17'. A

spring 21, of any suitable nature, which in the embodiment illustrated is of the blade-type, is interposed between the arm 16 and clamp 19, whereby the body of said clamp is urged towards the end 18 of said arm. The clamp 19, is mounted encircling the barrel 11, and is slidable therewith. The length of the end 18 is of such dimension that it may in pawl-like manner engage the barrel 11 when set in one of the grooved graduations, or otherwise suitably engage same due to friction, whereupon arm 16 is positioned substantially parallel to and along the barrel 11.

The position of element 15 on piston 12, is such, that the distance from the underside of flange 15' to the tines 17', equals the distance between the bottom of said piston to the pawl or pointer 18, because said element 15, is so set that upon completion of the full permitted movement of piston 12 into the cylinder 11, the bottom of said piston is exactly at said pointer's edge.

It is obvious that the amount of liquid which will be ejected at any time is that which is between the bottom of the piston 12, and the graduation 25 at which the pointer or pawl-end 18 is. In the set-up shown in Fig. 2, such amount or volume which will be ejected upon movement of the piston 12 into the barrel 11, would be all liquid 13, in the barrel above the graduation *c*. Now, if it is desired to discharge such volume of liquid as is between the graduations *c* and *b*, the operator first presses arm 16 towards the piston 12, to release element 18 from engagement with the barrel 11, which however will stress spring 21. Clamp 19, is now slid downward along barrel 11, until element 18 is at *b*, whereupon arm 16 is let go, so that 18 becomes engaged at *b* and thus locks the dosage gauge shown in Fig. 1, in fixed position on the syringe 10. The tines 17' have thus been lowered exactly the distance between the graduations *c* and *b*. It is evident that the limit of movement permitted the piston 12 further into the barrel 40 11, determined by the interception by the tines 17' of the flange 15', at the setting described, would be exactly that between the said graduations *c* and *b*.

Injection into a large number of animals, of 50 small identical volumes of material, can be accomplished with precision with the above device. Of course, the dosage gauge described can be easily detached from one syringe and applied to any other as may be desired. Settings for unequal doses, are likewise easily made. Such uses

and manipulations are here given as mere matter of example.

In the modified form illustrated in Fig. 4, the element 17' is on an arm 16' which is carried by the member 19, instead of on element 18 as an extension thereof.

In Fig. 4, said element 18 is manipulated by pressing at 16''. In all other respects, the manner of use and operation of said modified structure is identical with the mode of use and operation of the embodiment shown in Fig. 2.

This invention is capable of various forms and numerous applications and uses without departing from the essential features herein disclosed. It is therefore intended and desired that the structures herein set forth be deemed illustrative and not restrictive and that the patent shall cover all patentable novelty herein set forth; reference being had to the following claims rather than to the specific embodiments herein to indicate the scope of this invention.

I claim:

1. In an article of the character described, the combination with a syringe including a cylinder having a piston slidably mounted therein and extending outwardly therefrom, and a stop extending laterally from the external portion of the piston, of a member slidably mounted on the cylinder, a pointer member pivotally secured to the slidable member, adapted to engage the cylinder, a spring means interposed between said members, adapted to maintain said engagement, an arm secured to one of said members and extending towards said external portion of the piston, and an element extending from said arm intermediate the cylinder and stop and in the locus of movement of said stop.

2. An article as defined in claim 1, wherein the cylinder is marked with graduations along at least a portion of the locus of movement of the pointer member.

3. An article as defined in claim 1, wherein the cylinder is marked with grooved graduations along at least a portion of the locus of movement of the pointer members; said pointer member being adapted to engage the cylinder in any of said grooved graduations.

4. In an article of the character described, the combination with a syringe including a cylinder having a piston slidably mounted therein and extending outwardly therefrom, and a stop extending laterally from the external portion of the piston, of a member slidably mounted on the cylinder, an arm pivotally secured to said mem-

ber, positioned along and spaced from the cylinder and piston, an element extending from said arm intermediate said stop and cylinder and positioned in the path of movement of said stop, a second element extending from said arm, adapted to engage the cylinder, and a spring means interposed between said arm and the member on the cylinder, adapted to maintain said engagement.

5. An article as defined in claim 4, wherein the cylinder is marked with graduations along at least a portion of the locus of movement of the second element.

6. An article as defined in claim 4, wherein the cylinder is marked with grooved graduations along at least a portion of the locus of movement of the second element; said second element being adapted to engage the cylinder in any of said grooved graduations.

7. An article as defined in claim 4, wherein the pivotal connection of the arm is intermediate the ends of the arm.

8. An article as defined in claim 4, wherein the pivotal connection of the arm is intermediate its ends, and the spring means is interposed between said arm and the member on the cylinder.

9. In an article of the character described, the combination with a syringe including a cylinder having a piston slidably mounted therein and extending outwardly therefrom, and a stop extending laterally from the external portion of the piston, of a member slidably mounted on the cylinder, an arm carried on said member, an element extending from said arm intermediate said stop and cylinder and positioned in the path of movement of said stop, a second element pivotally secured to the slidable member, adapted to engage the cylinder, and a spring means interposed between the slidable member and the second element, adapted to maintain said engagement.

10. An article as defined in claim 9, wherein the cylinder is marked with graduations along at least a portion of the locus of movement of the second element.

11. An article as defined in claim 9, wherein the cylinder is marked with grooved graduations along at least a portion of the path of movement of the second element; said second element being adapted to engage the cylinder in any of said grooved graduations.

JOSEPH VONDRAK.
